Richard Hale Hinck
ATTORNEY.

UNITED STATES PATENT OFFICE.

HAROLD N. PALMER, OF NEW LONDON, CONNECTICUT.

APPARATUS FOR CLOSING WINDOWS AT PREDETERMINED TIMES.

1,187,381.

Specification of Letters Patent. Patented June 13, 1916.

Application filed August 16, 1915. Serial No. 45,680.

To all whom it may concern:

Be it known that I, HAROLD N. PALMER, a citizen of the United States, residing at New London, in the county of New London, in the State of Connecticut, have invented a certain new and useful Improvement in Apparatus for Closing Windows at Predetermined Times, of which the following is a specification, reference being had to the accompanying drawings.

The object of this invention is to provide a reasonably cheap and simple mechanism, controlled as to its action by clock mechanism, whereby windows which are opened for ventilative purposes during the night may be automatically closed at a predetermined hour in the early morning, thus rendering it unnecessary for a person sleeping in the room to arise for the special purpose of closing the window; in fact, rendering it unnecessary for the said sleeper to tax his mind with the matter of closing such windows. It is my intention further to so construct the said window closing apparatus that it may be readily applied to windows and window casings as now commonly constructed.

My said invention is illustrated in and by the annexed drawings, Figure 1 being an elevation of a portion of a window and its casing, having applied thereto closing apparatus embodying my present improvement, and Fig. 2 is a relatively enlarged, detached, view of the said closing apparatus. Fig. 3 is a further enlarged view of the means by which the window is latched in its raised (open) position, and Fig. 4 is a view of a lever which is operated, by clock mechanism, to release the latching mechanism just referred to. Fig. 5 is a detached, plan, view of a plate or bracket, by means of which the window-operating mechanism is connected to the window sash. Fig. 6 is a longitudinal, central, sectional view of plunger mechanism which is specially provided to prevent the too rapid closing of the window.

In these drawings the numeral 10 indicates a window frame and 11 denotes a sash slidably mounted in said frame. Secured to the top of the sash is a plate 12 which overhangs the inner face of the sash, and immediately below said plate is clock mechanism of ordinary construction, including "alarm"

mechanism, which is secured to the window sill 14. Secured to, and depending from, the plate 12 is a rod 15 whose lower end bears a packed piston 16 that is slidably mounted in a tube 17 which latter is secured to the window sill. When the window is raised the piston head 16 is drawn upward in tube 17 and, when the said window is released, the piston plunger and the tube 17, cooperate, with a restraining and cushioning effect, to prevent the sash from coming down with a "run". Instead, however, of the described piston plunger other restraining means could be utilized if desired as, for example, ordinary cords, and weights of slightly less weight than the window.

Mounted to slide in a guide-ring 18, secured to the tube 17, is a rod 19 whose upper end is offset, as seen most clearly in Fig. 3, said offset portion being connected with a bell-crank-lever 20 which is fulcrumed to the tube 17 at 21; the other end of said bell-crank-lever being connected to a bolt or latch 22 which is adapted to slide in an opening in the tube 17 in a direction, as here shown, at right angles to the longitudinal center of the rod 15, and so as to engage and enter notches 23 in said rod 15 and thus retain the said rod and the attached sash in their raised positions until such time as it is desired to have the window closed. In order to thus release, and close, the window I connect the lower end of rod 19 with one end of a lever 24 (see Fig. 4); the other end of said lever being located in the path of any movable part of a clock alarm, and in such relation to said alarm that, when the latter "goes off" at a predetermined hour, the rod 19 will be slid downward a distance sufficient to withdraw the end of bolt 22 from latching engagement with the notch of piston rod 15 and thus permit the sash to drop to its closed position. If it should be desired to assist the sash positively in its descent a steel tape 25 may connect the plate 12 with a revolute drum 26 which latter may be operated by a barrel spring within the said drum.

My described window-closing device may be readily applied to windows as ordinarily constructed and it provides means for automatically closing such windows at predetermined times.

Having thus described my invention I

claim as new and wish to secure by Letters Patent:—

A window closing apparatus, including an inclosed rod member connected to the window sash, an additional rod member having vertical movement, an angular lever, one arm of said lever being connected to the upper end of said additional rod member,

the other arm of said angular lever being equipped to engage and retain the first referred to rod member in elevated position, said additional rod member also being equipped with a fulcrumed lever at its lower end, and means adapted to actuate said lever at a predetermined time.

HAROLD N. PALMER.
